RADIOTRANSMISSION

George Wald, Mount Clemens, Mich.

Application June 24, 1933, Serial No. 677,496

5 Claims. (Cl. 250—2)

This invention relates to the art of radio transmission and is especially applicable to television.

An object of this invention is to transmit signal impulses, such as television impulses, on a high power low frequency carrier by first modulating a low power high frequency by means such as a television camera circuit and deforming the low frequency transmission carrier by the high frequency waves, receiving the low frequency carrier and reconstructing therefrom the high frequency carrier from which the transmitted signals may be reproduced.

With this object obtained a broad wave band television current may be accommodated without affecting the width of the main radio carrier wave band. By the use of this invention the trouble and uncertainty experienced with the reception of high frequency signals is eliminated as is also the trouble due to broad wave bands when the long wave carrier, deformed directly by the signal circuit, is used.

The objects of the invention will be further apparent from the following detail description taken in connection with the accompanying drawing, in which:—

Fig. 1 is a diagram of a curve produced by a long wave high powered radio transmission carrier mixed with a low power high frequency current.

Fig. 2 is a diagram similar to Fig. 1, in which the high frequency intermediate carrier has been modulated by television current.

Fig. 3 is a diagrammatic view of transmission circuits embodying this invention.

Fig. 4 is a diagrammatic view of receiving circuits embodying this invention.

A television signal current is produced in the device 1 by a means not shown, but which may be any means responsive to visible signals by which an image is scanned and a current produced dependent in magnitude on the intensity of light at the points scanned. The television signal current may be amplified by a device 2 the detail of which is not sketched. The amplifying circuit including the amplifier 2 is inductively coupled to an oscillating circuit including an oscillator 3. The oscillator 3 and its circuit are so constructed as to produce a low power high frequency carrier which will be modulated by the inductive coupling with the amplifier circuit.

The oscillating circuit is inductively coupled to a frequency mixing circuit including the mixing tubes 4. The frequency mixing circuit is also inductively coupled to an oscillating circuit including a high power oscillator 5. The circuit,

frequency mixer and source of potential for the circuit are such as to produce high power low frequency oscillations which are deformed by the frequency mixing circuit, that is to say, by the low power high frequency oscillations which have already been modulated by the television signal current. The frequency mixing circuit including the mixing tube 4 is inductively connected by the transformer 6 to an antenna circuit including an antenna 8.

A circuit is inductively connected to the oscillating circuit including the oscillator 5 and includes the auxiliary secondary 9. A rectifying circuit, including a rectifier 10, is inductively connected to the last named circuit and is supplied by power from the low power auxiliary secondary 9. The rectifying circuit is connected, as shown, to the oscillating circuit including the oscillator 3 in such a manner as to stop the oscillations of the oscillator 3 when the potential on the oscillator circuit 5 is near zero and the potential in the rectifying circuit reaches a predetermined minimum. A choke coil may be connected in series with the rectifier 10, booster source of power 11 and the oscillating circuit 3 so as to make the power supplied by the rectifier 10 of an amplitude nearly equal at all times except when the potential in the oscillator circuit 5 is at or near the zero point. On account of the coupling between the rectifying and the oscillating circuit 5 the power supplied by the rectifier 10 will be dependent upon the oscillations of the circuit 5 and thus the oscillator 3 will be silenced twice during each cycle of the oscillator 5, that is whenever the potential of the oscillating circuit 5 is at or near zero.

The result of the transmitting station circuit, diagrams of which are illustrated in Fig. 3, is shown on the diagrams Figs. 1 and 2. The lines 12, Fig. 1, illustrate the contour of the power output of the oscillator 3 when its circuit is not modulated by the television signal current. The even lines 13 illustrate the power output of the oscillator 5 without deformation, and the zigzag lines 14 illustrate the power output of the modulating circuit 4 when mixed with and deformed by the superimposition of the high frequency low power oscillations. When the potential, as illustrated by the lines 13, approaches the zero line 15 the oscillator 3 stops, thus making the power output of the oscillator 3 zero as indicated by the straight lines 12 at 15, 15.

Fig. 2 is similar to Fig. 1 except that in this illustration 12a indicates the power output of the oscillator 3 when its wave is modulated by the 55

television signal circuit represented by the curve 18. The zigzag line 14a represents the carrier wave deformed by the high frequency low power wave as modulated by the television signal current. The shape of the resultant wave 14 or 14a will depend upon the relative ratio of the superimposed power waves of the oscillators 3 and 5. While in such a scheme the television current modulation will be but a very small percentage of the power radiated from the antenna, such apparent deficiency is taken care of by the use of a local oscillator at the receiver as hereinafter explained.

The radiation of power from the antenna 8, as shown by the curve 14a, is received by the antenna 17 of the receiver circuit which is tuned to the long wave length of the carrier wave 18, that is to say, of the oscillations of the circuit 5. The signal is amplified by a tube 18 and applied to a high frequency transformer 19 and the low frequency transformer 19a. The primaries of these two transformers 19 and 19a are connected in series with a by-pass condenser across the primary of transformer 19. These two transformers with proper condensers across their secondaries are in such tuned relations as to respond only to desired wave lengths; the transformer 19 responding to the high frequency waves while transformer 19a to the low frequency waves. The by-pass condenser across the primary of transformer 19 acts as an antenna for the high frequency waves causing responsive oscillations in its tuned circuit. In this way the carrier wave is broken into its component parts. A circuit including the secondary of the transformer 19 includes an amplifier 20 and is conductively connected to an oscillating circuit including an oscillator 21 and a mixing tube 22. The local oscillator 21 is adjusted to oscillate with the same frequency as the oscillator 3, that is, in a high frequency, as illustrated by the curve 12 and is made to harmonize with the frequency of the incoming signal by the mixing tube 22. Thus, the local oscillator current is modulated by the incoming signal. The high frequency oscillations in the local oscillating circuit 21 are further amplified by a tube 23 and are detected by a tube 24. The television current signals, as detected by the tube 24, are applied across the television amplifier 25 and the effective current therefrom is applied to a receiver, not shown, through the circuit.

In telephono-vision when the time of transmission is divided and part of the carrier is used for sound and the other part for image, the audio signals may be applied to a circuit 7 connected as shown in Fig. 3. The signals thus transmitted by the antenna 8 and received by the antenna 17 can be made audible by a circuit 1a connected to the secondary of the transformer 19a (Fig. 4), and the circuit 1a may be connected to a long wave radio circuit and sound reproduced therefrom in a manner well known in the art.

It will be evident that the silencing of the oscillator as indicated at 15 will cause an interruption of the transmission of television signals. This interruption will not cause any lack of fidelity in the received signals if the rate of scanning is increased over that normally used. Since the number of points scanned will, in the absence of accident, have no relation to the fre-

quency of the oscillator 3 the missing impulses will not recur at the same points on the image.

It will be understood that having described the method employed those skilled in the art will at once be able to devise many different circuits for practicing the method. While some of such circuits have been illustrated and described I do not intend to limit myself to this precise circuit. Parts of the invention may be used without the whole, additions may be made thereto, and various changes may be made in the details of construction, of the apparatus and of the circuits, within the scope of the appended claims, without departing from the spirit of this invention.

I claim:

1. In the art of radio transmission, the method including modulating at a transmission station a low power high frequency carrier by a signal current deforming a relatively high power low frequency carrier by the said modulated high frequency carrier, transmitting and receiving the low frequency carrier so deformed, reconstructing therefrom at a receiving station high frequency waves corresponding to the modulated high frequency carrier produced at the transmitting station, and reproducing from said high frequency waves, signals corresponding to those influencing the signal circuit.

2. In a radio transmission set, a signal circuit, an oscillating circuit adapted to oscillate at a relatively high frequency, means for modulating the oscillating circuit by the signal circuit, means for producing a relatively high power low frequency carrier, and means for deforming said carrier by said high frequency circuit.

3. In a radio transmission set, a signal circuit, an oscillating circuit adapted to oscillate at a relatively high frequency, means for modulating the oscillating circuit by the signal circuit, an oscillating circuit adapted to oscillate at a relatively low frequency, means for deforming the wave produced by the low frequency current by said high frequency current by superimposition, and means for choking the high frequency circuit when the potential in the low frequency circuit is at and near zero.

4. In radio apparatus, a signal circuit, an oscillating circuit adapted to oscillate at a relatively high frequency, means for modulating the oscillating circuit at the signal circuit, means for producing a relatively high power low frequency carrier, and means for deforming the carrier by said high frequency circuit, all at a transmitting station, means for transmitting and receiving such deformed low frequency carrier, means for reconstructing at a receiving station a high frequency current corresponding to the modulated high frequency current at a transmitting station, and means responsive to said high frequency current for reproducing signals.

5. In a receiving set adapted to receive a relatively high power low frequency carrier deformed by a relatively low power high frequency current, a receiving circuit tuned to such low frequency, an oscillating circuit tuned to such high frequency and including a power oscillator, means for influencing said oscillating circuit by the receiving circuit, and a signal circuit responsive to said oscillating circuit.
